(57) **CLAIM**

I claim the ornamental design for the cup holder adaptor for holding items, as shown and described.

DESCRIPTION

FIG. 1 is a top perspective view showing our new design of a cup holder adaptor for holding items;
FIG. 2 is a bottom perspective view thereof;
FIG. 3 is a top view of FIG. 1 thereof;
FIG. 4 is a bottom view of FIG. 1 thereof;
FIG. 5 is a side view of FIG. 1 thereof;
FIG. 6 is a side view that opposes the side view of FIG. 5 thereof;
FIG. 7 is a back view thereof; and,
FIG. 8 is cross-sectional perspective view thereof.
